(57) **CLAIM**

The ornamental design for a shot dispenser, as shown and described.

DESCRIPTION

FIG. 1 is a perspective view of a shot dispenser showing our new design including its bottom tray, nestable top tray, and removable pouring funnel, with the ghosted outlines indicating an example of tubes that may be held in the shot dispenser and used to contain a liquid or the like;

FIG. 2 is a plan view thereof;

FIG. 3 is an elevation view thereof; and,

FIG. 4 is a bottom view thereof.
